UNITED STATES PATENT OFFICE

CLAUDE HERBERT BRIGHT, OF MEMPHIS, TENNESSEE

FOUNTAIN INK PAD

Application filed April 24, 1928. Serial No. 272,525.

This invention relates to fountain ink pads in which a wick is adapted to feed ink to a stamping surface by capillary attraction from a reservoir.

5 The object of the invention is to provide a very compact ink stamping pad in which a reservoir is ordinarily maintained in water-tight separation from the pad element itself, but which by a very simple 10 movement of one of the parts thereof can be moistened by ink from the reservoir without necessitating the usual smearable application of ink from a bottle.

Another object of this invention is to provide 15 a fountain ink pad of the character referred to which can be very cheaply manufactured and which can be made of very few elements which can be readily assembled and disassembled for refilling the 20 reservoir or for repairing or replacing the parts thereof.

Other objects of the invention will appear as the detailed description thereof proceeds.

In the drawings:

25 Figure 1 is a plan view of the invention; Figure 2 is a side elevation thereof; and Figure 3 is a vertical section on the line 3-3 of Figure 1.

As shown clearly in the drawings, the 30 invention comprises a rectangular box-like casing 1, having the upper inside edges thereof provided with a rabbet 2, forming a shoulder 3 around the top of the box-like casing. On this casing shoulder 3 there is seated partition 4 provided with a door 5 which is hinged by hinge 6 to the main part of the partition 4.

Resting on the partition 4 and of approximately 35 the same length as the casing 3, is a pad support 7; and arranged on this pad support is a layer of wick material 8 having one end thereof secured to hooks 9 at the free end of the door 5. This wick material 8 extends from the hook along the 40 door 5 and along the rear part of the partition 4 through an aperture 10, formed in the support 7, and up along the rear end of the support 7 and along the top surface thereof and down the front end 11 approximately 45 into contact with the partition 4.

Arranged on top of the material 8 is a pad 12 of felt or similar material, and over this pad there is mounted a sheet of finer material 13, with which the stamp is adapted to be inked. The sheet 13 extends completely 50 over the pad 12 and down the ends of the wick 8 and the support 7; and in order to hold these parts in assembled relation a pair of filler slugs 14 and 15 are arranged between the sides of the casing 3 and the sheet 55 13.

Clamping screws 16 and 17 are screw-threaded into the ends of the casing 3 to engage the slugs 14 and 15, respectively, in order to clamp the several elements of the 60 65 pad in assembled relation.

A cover 18 may be hinged or otherwise suitably secured to an edge of the casing 3 to cover the pad when not in use and to prevent waste of material by evaporation. 70

In order to maintain the door 5 and the wick 8 out of contact with the ink 19 in the casing the door is provided with an arm 20 extending through a slot 21 in the side 75 22 of the casing 3; and the arm 20 is of such length that its free end may rest upon one end of a slide member 23 which is secured by screws 24 extending through a slot 25 in member 23 into screwthreaded relation with the side 22. 80

When it is desired to ink the pad, the side member 23 may be withdrawn into the dotted line position, shown in Figure 2, to permit the arm 20 and the door 5 connected thereto to fall by gravity, thus immersing 85 the door 5 and the part of wick 8 secured thereto in the ink 19. In the immersed position of the door 5, it will be obvious that the wick will draw ink from the reservoir up by capillary attraction to the pad 90 12 to moisten the sheet 13 suitably for applying ink to a stamp.

What I claim is:

1. A casing adapted to contain a liquid and having a shoulder formed around the 95 upper inside edges thereof, a partition seated on said shoulder and having an aperture therethrough, a door carried by said partition and adapted to close said aperture, a wick secured to the door and extending 100

along said door and partition to one end of the casing, a support mounted on said partition above said wick, a pad mounted on said support in contact with said wick, and means 5 for clamping said pad and partition in assembled position in said casing.

2. A fountain ink pad comprising a casing adapted to contain a liquid, a partition in said casing above said liquid, a pad mounted 10 on said partition, means for engaging both said pad and partition to hold same in assembled relation in said casing, and means hingedly connected to said partition to feed liquid from said casing to said pad.

15 3. A fountain ink pad comprising a casing adapted to contain a liquid, a partition in said casing above said liquid and having an aperture therethrough, a door carried by said partition to close said aperture and 20 adapted to fall by gravity into said liquid, a pad mounted above said partition and supported thereby, and means operably connected to said door to move it into closed position.

25 4. A fountain ink pad comprising a casing adapted to contain a liquid, a partition in said casing above said liquid and having an aperture therethrough, a door carried by said partition to close said aperture and adapted 30 to fall by gravity into said liquid, a wick secured to said door and extending along said door and partition to one side of said casing, a support mounted on said partition, a pad on said partition connected with said 35 wick, an arm projecting from said door through a side of said casing and adapted to move said door into aperture closing position, and means mounted on said side to engage said arm and hold the door in closed 40 position.

5. A fountain ink pad comprising a casing adapted to contain a liquid and having its upper inside edges rabbeted, a partition supported by the shoulders of the rabbeted 45 edges and provided with an aperture therethrough, a door hinged to said partition and adapted to fall by gravity into said liquid, an arm extending from the hinged end of said door and extending through the side of 50 said casing, slide mounted on said side and adapted to be moved under the free end of said arm to hold the door in aperture closing position, a pad mounted on said partition over said door, and means engaging the ends 55 of said pad to clamp the pad and partition is assembled relation on said casing.

6. A fountain ink pad comprising a casing adapted to contain a liquid, a pad clamped to said casing above said liquid and having 60 a part thereof movable into and out of said liquid, and means connected to said part to hold said part out of contact with said liquid.

7. A fountain ink pad comprising a casing 65 adapted to contain a liquid, and having its

inside upper edges rabbeted to provide shoulders on each side thereof, a partition seated on said shoulders, and having an aperture therethrough, a door on said partition to close said aperture, and a pad support mounted on said partition, said support and partition being provided with cooperating flanges to prevent lengthwise movement of said support on said partition.

8. A fountain pad comprising a container for ink, a pad positioned above the container said pad including a wick part coextensive therewith, located below said pad and in contact therewith, said wick having a part depending into the container and means for raising and holding the said depending part of the wick above the contents of the container to stop the feeding of ink to the pad.

In testimony whereof I affix my signature.
